UNITED STATES PATENT OFFICE.

DIGHTON A. ROBINSON, OF SEATTLE, WASHINGTON.

TIE-TAMPING MACHINE.

1,415,193.

Specification of Letters Patent. Patented May 9, 1922.

Application filed February 21, 1921. Serial No. 446,871.

To all whom it may concern:

Be it known that I, DIGHTON A. ROBINSON, a citizen of the United States, resident of Seattle, county of King, State of Washington, have invented certain new and useful Improvements in Tie-Tamping Machines, of which the following is a specification.

My invention relates to machines for the construction and maintenance of railroad tracks, and more particularly to machines for tamping and tucking the ballasting material under and between railroad ties in the operation of ballasting the tracks, and the general object of the invention is to dispense, as far as possible, with manual labor, now needed for the work, and provide a machine that will rapidly and efficiently ballast the tracks with a minimum amount of attendance.

A special object is to so mount the guns which carry the tamper bars that the lower end of any tamper bar, when the working vertical angle is adjusted or changed during the progress of the work, will swing around an imaginary center near the lower edges of the ties; and means for adjusting this center for different sizes of ties in order to positively tuck the ballasting material thoroughly and firmly under and around the ties.

Other objects are to provide a machine of this class that will be light of weight, and, therefore, easy to handle in removing from and replacing on the track, which, by reason of traffic, frequently becomes necessary; and a machine which will possess superior flexibility and facility for placing and adjusting the tamping bars to the various positions necessary to do rapid and efficient work.

The invention consists generally in certain novel constructions and combinations, all as hereinafter described and particularly pointed out in the claims, with reference to the accompanying drawings forming a part of this specification, in which,

Figure 1 is a side elevation in section of a machine constructed in accordance with my invention, the section being taken on the line 1—1 of Figure 2,

Figure 2 is an end elevation of the machine, partly in section, on the line 2—2 of Figure 1,

Figure 3 is a detail sectional view of one of the air cylinders and cable connections,

used for quickly moving the tamper guns transversely of the track,

Figure 4 is a sectional view on the line 4—4 of Figure 3,

Figure 5 is a detail sectional view, of one end of one of the air cylinders and piston therein,

Figure 6 is a cross section of one of the valves used for controlling and moving the air guns to their various positions, the section being taken on the line 6—6 of Figure 9,

Figure 7 is a side elevation of a battery of the controlling valves,

Figure 8 is a plan view of Figure 7,

Figure 9 is a section on the line 9—9 of Figure 8,

Figure 10 is a side elevation of one of the tamper guns and sectional view of the air cylinder and supporting linkage, illustrating the method of obtaining the swinging motion of the tamper bars around an imaginary center or point near the lower edges of the ties,

Figure 11 shows a modified method of detachably connecting the tamper guns to the piston rods and cross heads of the air cylinders, and,

Figure 12 is a modified form of piston control.

In the drawings, 15 represents the side members and 15^a the end members of the skeleton rectangular frame of the machine, preferably constructed of channel bars, rigidly secured together in the conventional way. Anti-vibration truss rods 16 and 17 are adjustably secured to the end frame bars 15^a and supported in suitable central struts 18. Axles 19 have suitable journals (not shown) on the frame 15 and flanged wheels 20 gauged to run upon the rails 21 are secured to the axles 19 as in ordinary railroad car construction.

Near the wheels 20 are mounted rollers or wheels 22 in brackets 23 for the purpose of quickly running the machine off the track sideways on rails or equivalent means, after it has been raised off the rails by suitable track jacks. Vertical posts 24 and 24^a are secured to the side members 15 of the frame and rigidly connected some distance above the frame 15 by cross girders 25 and 26 and upper guideway bars 27 and 27^a. A suitable light constructed roof 28 preferably covers the machine. Upon frame bars 26^b, connecting the cross girders 26, is supported an

air compressor 29 and an internal combustion or other suitable motor 30 to drive the compressor 29 is mounted adjacent thereto upon similar frame bars 26^c. While the 5 motor may be coupled direct to the compressor by means of a friction clutch 31, it is preferable in using a high-speed engine or motor to drive the compressor by means of suitable reduction gearing 32.

10 The clutch 31 may be controlled by a suitable lever 33 (Figures 1 and 2). Compressed air is conducted from the compressor 29 through a pipe 34, having a conventional pressure gage 35 to a compressed air tank 15 or reservoir 37, supported upon and located transversely between the frame members 15. Upon this tank is preferably supported the air cylinders 38 used for the lateral adjustment of the tamper guns 39 and lateral 20 guideways 40 and 41 are also secured to the tank 37. The machine comprises one or more tamper units working oppositely on each side of the tank 37, as shown in Figure 1, and as these opposite units are of precisely 25 the same construction, I will describe the right hand unit only, it being understood that the same description applies in every particular to the left-hand unit.

Three air-controlled cylinders are made 30 use of in the operation of each tamper unit, a cylinder 38 as heretofore described for the lateral adjustment of the tamper gun 39, a cylinder 42 for the angular or tilting adjustment and a cylinder 43 for the vertical 35 adjustment of the gun (Figure 1). The construction and operation of all the cylinders and pistons are substantially the same except in some particulars with reference to the cylinder 38, which will be hereinafter 40 explained.

Referring to Figures 4, 5, and 10, the cylinder 38 is provided with heads 44 and 45 having stuffing boxes 46 through both of which a piston rod 46^a passes, while the cylinders 42 and 43 have one closed cylinder head 45^a from which a supporting lug 45^b projects. Ports 47 and 48 are arranged in all cylinders near the heads by which air under pressure is admitted and exhausted. A piston 49 is firmly secured to the piston rod 46^a in cylinder 38 and to the piston rod 50 in cylinder 42 in any suitable manner, as by shrinkage or threaded means and is provided with the peripheral portholes 51 and 52, 55 opening in opposite directions through lateral ports 51^a and 52^a in the cylinder chambers 53 and 54. Piston valves 55 actuated by coil springs 56 to seat against rods or wires 56^a and close the ports 51^a and 52^a are arranged in the peripheral ports 51 and 52 of the piston 49. Air under pressure is admitted to one end of the cylinders and exhausted from the other through the ports, according to the direction it is desired to move the 65 piston 49, and as the piston closes the cor-

responding port, air is trapped between the piston and the cylinder head, forming an air cushion, the lateral ports 51^a and 52^a, being then closed by the piston valves 55. When it is desired to return the piston, the 70 air is exhausted from the end opposite the air cushion and compressed air is admitted through the port adjacent the cushion, as shown in Figure 5, when the piston valve 55 will be depressed to uncover the port 51^a 75 and air under pressure will enter behind the piston 49, moving it towards the opposite end of the cylinder. The distance between the peripheral ports 51 and 52 in the piston and the ends of the pistons is sufficient to 80 prevent the piston ports passing (under ordinary conditions) the ports in the cylinder, which would prevent the piston from being returned should leakage occur to destroy the air cushion. The piston may be moved to 85 and retained in any desired intermediate position in the cylinder by admitting and exhausting the air to the proper degree and thereafter closing both the admission and exhaust ports. The pneumatic tamper guns 90 39 are of ordinary or standard construction, well known in pneumatic hammers or like tools, and characterized by imparting rapid strokes or hammer blows to the inserted tool. Tamper bars 57, which may be of various 95 forms suited to various conditions and kinds of ballasting material, are inserted in the guns 39 and air under pressure is supplied to the guns through ports 58 and exhausted from the guns through ports 59. 100

Referring particularly to Figure 10, it will be noted that the gun 39 is detachably connected to the piston rod 50 of the cylinder 42 by means of a crosshead 60 to which the rod is secured by threaded or other means. The gun 39 may be detachably fastened to the crosshead 60 by bolts 61, as shown in Figure 10, or by inserting the gun 39 in a crosshead 60^a and securing it by means of a set screw 62 or other equivalent 105 means, as shown in Figure 11. The crosshead 60 is slidably supported upon a bar 63 rigidly secured to the cylinder in any suitable manner, as by flanges 64 and bolts 65. 110

At the outer end of the cylinder 42 is a swinging arm 66 having a longitudinal slot 67 in which a pin 68, passing through the cylinder head 45^b, is adapted to slide. This arm is free to oscillate with the cylinder 42 120 and move across the machine with it and forms a convenient support for the control valves, as will hereinafter appear. A radius bar 69 is pivoted to the pin 68 and extending towards the center of the machine, is 125 swingingly connected at 70 to a horizontal slide 71 arranged in the guideways 40 and 41 on the body of the compressed air tank 37. A lever 72 is fulcrumed at 73 on the radius bar 69 and is pivoted at 74 to the slide 71 130

and at 75 to a block 76 adjustably connected to the bar 63 by means of an adjusting screw 77. This lever 72, in conjunction with the radius bar 69 and cylinder bar 63, swingingly supports the inner end of the gun 39 and the three pivot points 73, 74 and 75 of the lever 72 are located in such relationship to each other and to the pivot points 70 of the radius bar 69 that vertical adjustment of the outer end of the gun 39 will have substantially no effect on the working position of the lower tamping end of the bar 67, as indicated in the full and dotted line positions shown in Figure 10. By adjusting the gun bar 63 vertically with relation to the pivot point 75, the location of the tamping point may however be varied vertically to adapt the tamping bar to the depth of the ties, and this adjustment may be performed by the screw 77.

I prefer to make the radius bar 69 in two sections and arrange the screw between the two sections. A rod 78 is secured to the piston 49 in the cylinder 43, as shown in Figure 5, and adjustably connected at 79 to the flange 64 by pins fitting suitable holes 79^a or a slot may be arranged in the bar, in which the rod 78 may be adjustably secured. The cylinder 43 is pivotally supported at 30 its upper end upon a plate 80 slidably arranged in the upper lateral guideways 27 and 27^a. A pin 80^a passes through the ears 80^b of the plate 80 and through the lug 45^b of the cylinder head 45^a and upon this pin 35 is also swingingly mounted the slotted valve supporting arm 66. The cylinder 42 is raised or lowered and the angular position of the tamper bars 57 is regulated by controlling the position of the piston 49 in the 40 cylinder 43, as above described, and indicated by the dotted lines in Figure 10. It will also be noted by particular reference to this figure that the point X on the tamper bar 57 near the lower edge of the tie 81, by 45 reason of the peculiar and novel linkage and support of the tamper gun, will remain substantially in a fixed position at all practical vertical angles to which the tamper gun may be adjusted. This action will insure firm 50 tamping under the ties at the finish and uniform dependable ballasting of the track.

The point X may be vertically adjusted by means of the screw 77 to conform to different height and sizes of ties. The angular or semi-horizontal position of the tamper bar is adjusted during the initial and subsequent tamping operation by adjusting the position of the piston 49 in the cylinder 43 in the manner above disclosed, 55 and retaining it in position by closing both admission and exhaust ports 47 and 48.

The horizontal or lateral control and positioning of the tamper bar is accomplished by a similar control of the piston 49 in the 60 horizontal air cylinder 38. Referring to

Figures 1, 2, 3 and 4, it will be seen that the piston rod 46^a extends out through both cylinder heads 44 and 45 a suitable distance beyond which it carries duplicate cable sheaves 82 and 83 at one end and similar sheaves 84 and 85 at the other end. Duplicate sheaves 82^a and 83^a are mounted upon a frame bracket 86 at one side of the frame 15 and duplicate sheaves 84^a and 85^a are similarly mounted upon a bracket 87 at the 75 opposite side. Upper sheaves 82^b and 84^b are mounted upon brackets 88 and 88^a respectively. A cable 89 is fastened to an eye-bolt 90 in the frame post 24^a at one side of the machine (see Figure 4) and passes 80 around one of the piston rods, sheaves 82, forward around one of the sheaves 82^a, backwards around the other piston rod sheave 82, under the other sheave 82^a, thence upwards and over the sheave 82^b to the slide 85 80, to which it is attached.

At the opposite end of the piston rod 46^a, a cable 91 is similarly secured at one end to the frame post 24 at 90^a and running around the sheaves 84, 84^a, 85 and 85^a in a 90 similar manner is carried upwards over the sheaves 84^b and secured to the opposite end of the slide 80, which forms the overhead supports for the tamping unit. Below, the tamping unit is supported upon the slide 71 95 movable in the guide-ways 40 and 41 of the radius bar 69, and this slide is connected in a similar manner by cables 92 and 93 to the opposite ends of the piston rod 46^a. The cable 92 is attached to the frame member 15 by means of an eye-bolt 94 from which it runs backward and forward over the sheaves 83 and 83^a, thence downwards under a sheave 95 to the slide 71 to which it is attached. The cable 93 is similarly 100 attached to the frame at 96 and first running backwards and forwards around the sheaves 85 and 85^a, is then carried downwards under the sheave 97 and attached to the opposite end of the slide 71. It will 110 be readily seen that the movement of the piston rod in any one direction will carry both the upper and lower supporting slides simultaneously and equally in the same direction, opposite to that of piston, and that the slides will be carried four times the distance of the travel of the piston rod by reason of the multiple sheave arrangement, as above set forth, and will rapidly carry the tampering unit from one extreme 120 end of the tie across the machine to the other with the short length of piston travel available.

The controlling apparatus for the admission and exhaust of compressed air to and 125 from all the cylinders and also the supply of air to the tamper guns I prefer to mount on the arm 66, so that it will move laterally across the machine along with the tamper bars and be at all times convenient to the 130

operator. It consists of a battery of three four-way valves for the air cylinders and a two-way valve for the air guns, the details of which are shown in Figures 6, 7, 8 and 9 of the drawings. The valve housings 98 and 99 are mounted upon or made integral with a bar or plate 100 and the valves controlling the cylinders 38, 42 and 43 are substantially identical in construction, hence the description of one suffices for all three. The valve housings 98 (Figure 7) are provided with an admission port 101 (Figure 6) which is connected by suitable coupling 101^a to a pipe 102 (Figure 8) leading by means of a flexible hose 103 to the compressed air tank, 37. Opposite the admission port 101 is the exhaust port 104, which preferably is connected by a coupling 104^a to an exhaust pipe 105. At a right angle to these ports are arranged ports 106 and 107 in opposite sides of the valve housing and these ports are connected by means of couplings 106^a and 107^a to flexible hose 108 and 109 which are attached to the ports 47 and 48 of the air cylinders. A circular valve 110 accurately fitting the cylindrical bore of the valve housing and having semi-circular peripheral ports 111 and 112, is rotatably seated in the valve housing and held therein by a cover 113 (Figure 9). A valve stem 114 provided with an operating wheel or handle 115 is secured to the valve and projects through the cover 113. The peripheral ports 111 and 112 will register alternately with the admission ports 101 and exhaust port 104 when the valve 110 is turned 90 degrees and thereby alternately admit air to and exhaust it from the opposite ends of the air cylinders. As shown in Figure 6, air is exhausted through the port 111 and admitted through the port 112 and when the valve is turned ninety degrees, air will be admitted through the port 112 and exhausted through the port 111, as indicated by dotted lines in Figure 6.

When the valve 110 is turned forty-five degrees, all the ports are closed and the pistons in the corresponding air cylinder will then be held stationary between air cushions on both sides of the piston 49. By operating one or more of the valves therefor, the operator can at any time shift the position of the pistons in the cylinders 38, 42 and 43, and thereby accordingly move the tamper guns 39 to assume the different angular, vertical and lateral positions necessary during the progress of the work. The tamper guns are controlled by a smaller straight-way valve, mounted in the valve housing 99 and provided with a hand-wheel 116 or handle 116 by the operation of which air from the compressed air tank 37 to the gun 39 is controlled through a hose 117 and admitted to the gun through a hose 118. For the sake of clearness the air hose connections between the valves and cylinders have not

been shown completely in the drawings, but it will be readily understood that each of the cylinders 38, 42 and 43 has similar air connections to a corresponding valve 98.

The battery of valves for each tamper unit are operated from an operator's platform 120 and 121, preferably hinged to the frame members 15^a at opposite ends of the machine and provided with braces 122. The machine is transported on the rails by power supplied by the motor 30 to the wheels 20 through a suitable transmission gearing, preferably comprising a change speedgear and reverse box 123 (see Figures 1 and 2), bevel gears 124, shaft 125, bevel gears 126, transverse shaft 127, pinion 128 and gear 129 secured to the axle 19 of the driving wheels 20. The transmission gearing is controlled by the operator by means of a friction clutch 130 connecting the motor 30 with the gearing in 85 the gear box 123 in the ordinary way used in automotive practice.

In moving the machine on the rails, it is at times difficult for the operator to exactly locate it on the precise spot necessary to bring the tamper bars in the correct positions relative to the ties. I therefore provide what I term a "hand spotter" which simply consists of a sprocket wheel 133 on the idle axle 19^a (Figure 1), a chain 134 connecting the sprocket with a smaller sprocket 135 mounted upon a shaft 136 and provided with an operating hand wheel 137 in convenient position for the operator, as shown in dotted lines in Figure 1. A clutch 100 (not shown) may be provided on the axle 19 to disengage the axle from the wheel when the machine is run on the rails through the power transmission gearing. By means of this "spotter" the machine may be accurately located on the rails at the desired spot by turning the hand-wheel 137 which will turn the wheel axle 19.

In the operation of ballasting the track, the ballast cars dump a sufficient amount of ballast material in the center of the track to raise the ties and rails from about one to ten inches. The ballast is then scraped or spread to a corresponding depth above the top of the ties, after which pneumatic track jacks (not shown) but provided at each corner of the machine, lift the rails and ties the required height. The tamping operation with both tamper units is then started with the tamper bars in their elevated angle position and finished at their lowered angle position, solidly ramming the ballast under the ties, from both sides of the tie. When the tamper bars are to be moved from one side of the rail to the other, compressed air is turned into the lower ends of the cylinders 42 and exhausted from the upper ends, moving the pistons upwards to the limit of their stroke, after which the tamper units are moved laterally across the track by moving the pistons in the 130

air cylinders 38 to one or the other side as required, in the manner heretofore described.

Various modifications may obviously be made in the details of construction of this machine, without departing from the principle and scope of the invention, and while I have shown and described the locating and positioning cylinders for the tamper guns as being operated by compressed air, it is evident that a noncompressible fluidlike, for example, oil under pressure from a common circulating pump and controlled with substantially the same valve mechanism might be substituted for the control of the pistons 49 and I do not, therefore, confine the claims to the detailed construction as shown and described.

I claim as my invention:

1. The combination, with a tie tamping bar and its operating gun, of a fluid pressure controlled mechanism for projecting and retracting said bar and gun.

2. The combination, with a tie tamping bar and its operating gun, of a fluid pressure controlled mechanism for projecting and retracting said bar and gun and locking said gun against such movement during the tamping operation.

3. The combination, with a tie tamping bar and its operating gun, of a fluid pressure cylinder having a piston and piston rod connected with said gun for projecting and retracting said tamping bar and gun.

4. The combination, with a tie tamping bar and its operating gun, of a fluid pressure controlled mechanism for projecting and retracting said bar and gun and oscillating them on a horizontal axis adjacent the point of said bar.

5. The combination, with a tie tamping bar and its operating gun, of a fluid pressure cylinder having a piston, a rod connected with said gun for projecting and retracting said bar and gun, and means for tilting said cylinder to oscillate said bar and gun on a horizontal axis adjacent the end of said bar.

6. The combination, with a tie tamping bar, of a fluid pressure controlled mechanism for projecting and retracting said bar, and mechanism for oscillating said bar on a horizontal axis adjacent the end thereof.

7. The combination, with a tie tamping bar, of a fluid pressure cylinder and piston and a rod therefor connected with said bar for projecting and retracting it, and a second cylinder and piston having a rod connected with said first named cylinder for oscillating it vertically to rock said tamping bar on a horizontal axis adjacent the end thereof.

8. The combination, with a tie tamping bar and its operating gun, of a fluid pressure cylinder and piston having a rod connected with said gun for projecting and re-

tracting said bar and gun, means for tilting said cylinder to oscillate said bar on a horizontal axis adjacent the end thereof, and means for holding said tamping bar in its working position during such movement.

9. The combination, with a tie tamping bar, of a fluid pressure cylinder having a piston, a rod connected with said bar, mechanism for tilting said cylinder to rock said tamping bar on a horizontal axis, and means for holding said bar in its working position during such movement.

10. The combination, with a tie tamping bar, of a fluid pressure cylinder and piston having its rod connected with said bar, mechanism for tilting said cylinder to rock said tamping bar on a horizontal axis, and mechanism for holding the tamping end of said bar in its working position during such tilting movement.

11. The combination, with a tie tamping bar, of a fluid pressure cylinder and piston having its rod connected with said bar, mechanism for tilting said cylinder and tamping bar on a horizontal axis, a radius bar pivotally connected with said cylinder and having a normally stationary pivot, and means in connection with said radius bar for holding the end of said tamping bar in its working position during the tilting of said cylinder and bar.

12. The combination, with a tie tamping bar, of fluid pressure controlled mechanism for imparting a combined forward and backward and vertically oscillating movement to said bar, and means for holding said bar in its working position during the oscillating movement thereof.

13. The combination, with a tie tamping bar, of fluid pressure controlled mechanism for imparting a combined forward and backward and vertically oscillating movement to said bar, and means for holding said bar in its working position during the oscillating movement thereof, said means being adjustable to adapt the position of said tamping bar to the depth of the tie.

14. The combination, with a tie tamping bar, of fluid pressure controlled mechanism for imparting a combined forward and backward and vertically oscillating movement to said bar, and means for holding said bar in its working position during the oscillating movement thereof, said means comprising a pivoted radius bar connected with said mechanism remote from said bar and adjacent thereto for guiding and holding said tamping bar in its working position.

15. The combination, with a tie tamping bar, of a fluid pressure cylinder having a piston, a rod connected with said bar, a second fluid pressure cylinder and piston having its rod connected with said first named cylinder for oscillating said first named cylinder and said bar vertically, and means for

guiding said first named cylinder and holding said bar in its working position.

16. The combination, with a tie tamping bar, of fluid pressure controlled mechanism for projecting and retracting said bar and imparting an oscillating movement thereto on a horizontal axis, mechanism for shifting said bar and said fluid pressure operating means transversely, and means for holding 10 said tamping bar in its working position during its oscillating movement.

17. The combination, with a tie tamping bar, of a fluid pressure controlled mechanism for projecting and retracting said bar, 15 imparting an oscillating movement thereto, and means for holding said bar transversely.

18. The combination, with a tie tamping bar, of a fluid pressure cylinder and piston having its rod connected with said bar for 20 projecting and retracting it, a second cylinder having its piston and rod connected with said first named cylinder for oscillating it and said bar on a horizontal axis, and a third fluid pressure controlled cylinder and piston 25 for shifting said first named cylinders and said bar laterally to change the working position of said bar.

19. The combination, with a tie tamping bar, of a fluid pressure cylinder having its 30 piston connected with said bar for imparting a forward and backward movement thereto, upper and lower slides mounted for horizontal movement transversely of said bar, and a fluid pressure controlled mechanism for 35 oscillating said cylinder to tilt said bar and moving said slides horizontally to impart a transverse movement to said bar.

20. The combination, with oppositely arranged tie tamping bars, of fluid pressure 40 controlled mechanism for projecting and retracting said bars, said means being mounted to hold said bars in their projected position, and means for oscillating each of said bars on a horizontal axis adjacent the end thereof.

45 21. The combination, with oppositely arranged tie tamping bars, of fluid pressure cylinders having pistons and rods connecting said pistons with said bars for projecting and retracting them, said cylinders being mounted to oscillate vertically and impart a 50 rocking movement to said bars on a horizontal axis.

22. The combination, with oppositely arranged tie tamping bars, of fluid pressure 55 controlled mechanism connected with said bars for projecting, retracting, and rocking them on a horizontal axis and imparting a transverse movement to said bars for changing the working position thereof.

60 23. The combination, with a truck frame and supporting wheels therefor, of a tie tamping apparatus mounted in said frame and comprising a tamping bar, and fluid pressure controlled mechanism for projecting and retracting said bar, rocking it on a 65

horizontal axis and shifting said bar laterally to change the working position thereof.

24. The combination, with a frame and supporting wheels therefor, of oppositely arranged tie tamping bars and fluid pressure 70 operated cylinders having pistons and rods connected with said bars for imparting a forward and backward movement thereto, rocking said bars on a horizontal axis and shifting them laterally to change the working 75 position of said bars.

25. The combination, with a tie tamping bar, of a fluid pressure controlled cylinder and piston connected with said bar for reciprocating it, a second cylinder and piston 80 for imparting an oscillating movement to said first named cylinder and bar, valves controlling the flow of fluid to said cylinders, and an arm mounted to move with said first named cylinder and whereon said valves are 85 mounted.

26. The combination, with a tie tamping bar, of a fluid pressure controlled cylinder and piston connected with said bar for reciprocating it, a second cylinder and piston for 90 oscillating said first named cylinder and bar, a slotted arm having a sliding connection with said first named cylinder to move therewith, and valves mounted on said arm for controlling the flow of fluid to said cylinders. 95

27. The combination, with oppositely arranged tie tamping bars, of fluid pressure controlled cylinders and pistons connected with said bars respectively for reciprocating them, second cylinders and pistons for 100 tilting said first named cylinders and oscillating said bars on a horizontal axis, pivoted arms connected with said first named cylinders and suitable valves mounted on said arms and controlling the flow of fluid to said 105 cylinders.

28. The combination, with a tie tamping bar, of a fluid pressure cylinder and piston connected with said bar for reciprocating it, an oscillating radius bar pivotally connected 110 with said cylinder for guiding it vertically, a lever connected with said radius bar for holding said tamping bar in its working position, a second cylinder and piston connected with said first named cylinder for 115 imparting a vertical movement thereto, and rocking said tamping bar on a horizontal axis, and means for controlling the admission of fluid pressure to said cylinders.

29. The combination, with a tie tamping 120 bar, of a fluid pressure cylinder and piston having its rod connected with said bar, a fluid pressure controlled mechanism for raising and lowering said cylinder to tilt said tamping bar on a horizontal axis, a radius 125 bar pivoted at one end to said cylinder and having a normally stationary pivot at its other end, and a lever pivoted at a normally stationary point at one end and pivoted intermediate to its ends on said radius bar 130

and having means at its other end for connection with said tamping bar for holding it in its working position during the vertical movement of said cylinder.

- 5 30. The combination, with a pair of oppositely arranged tie tamping bars, of fluid pressure cylinders having their pistons connected with said bars for reciprocating them, radius bars pivotally supported above the
10 lower ends of said bars and connected with said cylinders, a second pair of cylinders having their pistons connected with said

first named cylinders for raising and lowering them and rocking said tamping bars on a horizontal axis, pivoted levers connected 15 with said radius bars and said first named cylinders for holding said tamping bars in their working position, and valves for controlling the flow of fluid pressure to and from said cylinders.

In witness whereof, I have hereunto set my hand this 14th day of Feby. 1921.

DIGHTON A. ROBINSON.
